BUILDING STRUCTURE

Filed July 31, 1931.

UNITED STATES PATENT OFFICE

FREDERICK M. VENZIE, OF PHILADELPHIA, PENNSYLVANIA

BUILDING STRUCTURE

Application filed July 31, 1931. Serial No. 554,218.

This invention, stated in its broadest terms, relates to a building structure and has more especial relation to a wall, partition, and ceiling construction in which so-called plaster boards are employed. The invention has co-relation to the subject matter disclosed in my co-pending application Serial No. 363,894, filed May 17, 1929.

In the disclosure aforesaid, I make use of 10 metallic clips in order to couple the plaster boards one with respect to another. Practice dictates that while such clips are efficient for the purpose designed, it is a more or less expensive operation.

15 The leading object of the present invention may be said to overcome this disadvantage and provide a construction in which in lieu of metal clips the plaster boards are coupled together by means of a specially designed tie 20 wire.

Other and further objects of the present invention reside in the provision of general details of construction and the arrangement, combination, and connection of parts for attaining the results sought by the foregoing 25 object.

The invention consists of the novel construction hereinafter described and finally claimed.

30 The nature, characteristic features and scope of the invention will be more fully understood from the following description taken in connection with the accompanying drawings forming part hereof, and in which:

35 Fig. 1 is a view partly in section and partly in elevation illustrating a ceiling and wall structure embodying the invention;

40 Fig. 2 is a view in perspective illustrating the application of one type of tie wire as applied to a channel iron;

Fig. 3 is a similar view illustrating a slightly modified form of tie wire;

45 Fig. 4 is a fragmentary view in elevation looking toward the left in Fig. 1 and illustrating the tie wire disclosed in Fig. 2; and

Fig. 5 is a view similar to Fig. 4, illustrating the tie wire as disclosed in Fig. 3.

For the purpose of illustrating my invention I have shown in the accompanying drawings forms thereof which are at present pre-

ferrered by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

Referring now to the drawings in detail, the reference numeral 5 designates the wall of a building paralleling which there is arranged a vertically disposed channel designated by the reference numeral 6 which is spaced from the wall 5 to provide an air space 7. The reference numeral 8 designates a horizontally arranged channel supported at its ends by the wall 5. The plaster boards are designated 9 and those plaster boards which are vertically disposed are secured with respect to the vertical channel 6, and those plaster boards which are horizontally arranged are secured with respect to the channel 8. In lieu of the metal clips shown in my patent application aforesaid, I make use of tie wires, a description of which will now be given, reference being first had to the tie wire disclosed in Fig. 2. Each tie wire comprises a single piece of elongated wire intermediate the ends of which it is formed into a loop 10 for engaging around either the channel 6 or the channel 8, as occasion may require. The free ends of the loop are then passed between adjacent plaster boards 9 and said free ends caused to pass in parallelism with the inner faces of the plaster boards 9, as clearly illustrated in Fig. 1. Thus, in the case of a ceiling the bottoms of the plaster boards abut upon the extended ends of the loops 10 and in order to secure the plaster boards in position with respect to the channel 8, those ends of the loops 10 which in erection are juxtaposed one with respect to another, are twisted as at 11, thus securely holding the plaster boards up against the channel 8. Obviously in the erection of the plaster boards 9 with respect to the side wall 5, the loops 10 of the tie wires are caused to engage around the vertical channel 6 and the

same manner of attachment pursued as just described.

In the case of the juncture of the ceiling and wall plaster boards, as shown at the upper left hand side of Fig. 1, the free ends of adjacent loops may be twisted together as at 12. With the plaster boards positioned as above described the inner faces thereof may have applied thereto a coating of plaster designated by the reference numeral 13.

Taking up now the construction disclosed in Figs. 3 and 5, the free end of each loop of the tie wire is bent to form an eye 14, see Fig. 3. Connected with respect to each eye 14 is another eye 15, and this eye 15 as shown in Fig. 3 terminates in a pair of prongs 16 arranged to be twisted as at 17 with respect to companion prongs of adjacent eyes 15. Obviously, instead of having prongs 16, the eye 15 might very well terminate in a single strand which could also be twisted with respect to a companion strand.

What is claimed is:

1. In a building structure, ceiling, partition, or wall-sections of plaster board, horizontal and vertical channels for supporting said plaster boards, tie wires each comprising a continuous piece of wire arranged between adjacent plaster boards, each tie wire being bent to engage around a channel and being provided with oppositely disposed prongs for abutting against the inner faces of adjacent plaster boards, adjacent prong ends being twisted together for maintaining said tie-wires including said plaster boards in position.

2. In a building structure, ceiling, partition, or wall-sections of plaster board, horizontal and vertical channels for supporting said plaster boards, tie wires each comprising a continuous piece of wire arranged between adjacent plaster boards, each tie wire being bent in the form of a loop to engage around a channel and being provided with oppositely disposed prongs for abutting against the inner faces of adjacent plaster boards, adjacent prong ends being twisted together for maintaining said tie-wires including said plaster boards in position.

3. In a building structure, ceiling, partition, or wall-sections of plaster board, horizontal and vertical channels for supporting said plaster boards, tie wires each comprising a continuous piece of wire arranged between adjacent plaster boards, each tie wire being bent in the form of a loop the channel engaging parts being disposed at right angles to plaster board abutting prongs, said tie wires engaging around a channel and being provided with oppositely disposed prongs for abutting against the inner faces of adjacent plaster boards, adjacent prong ends being twisted together for maintaining said tie-wires including said plaster boards in position.

4. In a building structure, ceiling, partition, or wall-sections of plaster board, horizontal and vertical channels for supporting said plaster boards, tie wires each comprising a continuous piece of wire arranged between adjacent plaster boards, each tie wire being bent to engage around a channel and being provided with oppositely disposed prongs for abutting against the inner faces of adjacent plaster boards, each of said prongs being provided with an eye operatively in engagement with an auxiliary prong, adjacent prong ends being twisted together for maintaining said tie-wires including said plaster boards in position.

FREDERICK M. VENZIE.
